CLAIM

The ornamental design for a helmet, as shown and described.

DESCRIPTION

FIG. 1 is a front perspective view of a helmet showing our new design;

FIG. 2 is a rear perspective view thereof;

FIG. 3 is a front elevational view thereof;

FIG. 4 is a rear elevational view thereof;

FIG. 5 is a right-side elevational view thereof;

FIG. 6 is a left-side elevational thereof;

FIG. 7 is a top plan view thereof; and,

FIG. 8 is a bottom plan view thereof.

The broken lines illustrate structure or features of the helmet that form no part of the claimed design. The dash-dot-dash broken lines illustrate the boundaries of the claimed design and form no part thereof.
